F. W. SMITH & C. DIPPLE, JR.
OPERATING DEVICE FOR BANK SCREEN WICKETS.
APPLICATION FILED JUNE 8, 1914.

1,163,785.

Patented Dec. 14, 1915.

UNITED STATES PATENT OFFICE.

FREDERICK W. SMITH, OF HEMPSTEAD, AND CHARLES DIPPLE, JR., OF BROOKLYN,
NEW YORK; SAID SMITH ASSIGNOR TO HECLA IRON WORKS, OF BROOKLYN, NEW
YORK, A CORPORATION OF NEW YORK.

OPERATING DEVICE FOR BANK SCREEN-WICKETS.

1,163,785.

Specification of Letters Patent. Patented Dec. 14, 1915.

Application filed June 8, 1914. Serial No. 843,692.

To all whom it may concern:

Be it known that we, FREDERICK W. SMITH and CHARLES DIPPLE, Jr., citizens of the United States, and residents of Hempstead and Brooklyn, in the counties of Nassau and Kings, State of New York, respectively, have invented certain new and useful Improvements in Operating Devices for Bank Screen-Wickets, of which the following is a specification.

Our invention relates to operating devices for bank screen wickets and has for its main object the production of an operating device of simple and compact construction adapted to easily and efficiently raise or lower a screen wicket at the will of the operator.

A further object of our invention is the production of an operating device which shall be hidden from the view and reach of persons outside of the bank window or counter so that any unauthorized manipulation thereof will be impossible.

Our operating device is also particularly desirable because of the small amount of space which it occupies and because of the fact that we have provided means whereby the screen wicket when closed, is automatically locked.

Our operating device is a distinct improvement over those heretofore used for the reason that a bank-teller or clerk is able, by the use of our device, to easily raise the wicket before him by simply pulling laterally a handle placed conveniently beneath his desk whereas formerly it has been necessary for the teller to reach over his desk in order to manipulate an operating device near the wicket or else to reach over and manually operate the wicket.

Further objects and advantages of the invention will appear in the following description, the invention consisting in the novel features and parts and combinations of the same hereinafter more particularly described and then specified in the claims.

In the drawings: Figure 1 is a front elevation of our improved operating device as applied to a bank screen wicket and showing various other portions of an inner side of a bank counter or desk and wall forming no part of our invention. Fig. 2 is a vertical cross-section taken on the line 2-2 of Fig. 1. Fig. 3 is a horizontal section taken

on the line 3-3 of Fig. 1. Fig. 4 is a perspective view of the operating device.

55

Similar figures of reference indicate corresponding parts in all the views.

Referring to the drawings: 1 indicates a bank screen wicket of the usual form and adapted to be raised vertically. The wicket slides, as is usually the case, in grooves or slots provided in the inner sides of the posts 2 and 2' forming parts of the ornamental metal work which, together with various other posts and glass panels, serve as a partition or wall between the outside and inside of the bank offices and which form no part of our invention. The screen wicket is adapted to slide behind a glass panel 4 which also forms a portion of the partition or wall above referred to. Stilts or rods 5 and 5', made preferably of metal in order to give them rigidity and strength are integrally united with or securely fastened to either end of the lower edge of the wicket 1 and extend downwardly for a considerable distance through the desk or counter 6 as illustrated. These stilts or rods 5 and 5' are supported at or adjacent their lower ends by the tie-rod or bar 7 which connects the 70 stilts together.

A drum 8 is provided with two slots or grooves around its periphery and is pivotally mounted on the stud 9 which is secured in any desirable manner to the under side 10 of the desk or counter 6. A flat operating-bar 11 is fastened to the upper face of the drum 8 by the bolts 12 as shown or by any other convenient means and is provided with a knuckle-joint 13 adjacent the periphery 90 of the drum 8. The operating-bar 11 extends outwardly and rests on a semicircular-shaped supporting-bar 14 attached at either end by the bolts 15 to the under side 10 of the desk or counter, the operating-bar being 95 provided at or near its end with an operating-handle 16.

Our invention contemplates the giving of a vertical motion to the screen wicket 1 by a partial rotation of the drum on its axis by 100 means of the operating-handle 16, or in other words a raising of the screen wicket by pushing the handle to the right and then a consequent lowering of the wicket by pushing the handle to the left.

105 A vertical motion is imparted to the

wicket 1 by means of two endless cables 20 and 20' which encircle the periphery of the drum 8 to which they are attached and which cables are also attached to the stilts 5 and 5', the direction of movement of each of these cables being controlled by a series of idlers arranged beneath the counter or desk, as will be described.

The cable 20 which for convenience we term the "upper cable" for the reason that it engages the upper slot or groove on the periphery of the drum 8 is preferably fastened to the drum 8 at or near a point marked "A" (see Fig. 3). From the point 10 A the cable 20 then takes a direction indicated by the arrows, first to the left passing over the idler 21 which is secured by its hanger to the under side 10 of the desk or counter, then back over the idler 22 which is 15 mounted on a bracket 30 which is bolted or otherwise secured to a post 3. The cable then takes a downward direction passing over an idler 24 which is mounted on a bracket 31 which is also bolted or otherwise 20 secured to the post 3. After passing over the idler 24 the cable runs upward to and over the idler 23 which is also mounted on the bracket 30. The cable then passes 25 around the drum 8 and back to the starting point A.

A cable-clamp 35 which is preferably an integral part of the tie-rod 7 is used to clamp the cable 20 to the stilt 5. Obviously then, a movement of the drum 8 by means of 30 the handle 16 in a counter clockwise direction forces the screen wicket 1 upward, and a consequent turning of the drum in a clockwise direction forces the wicket downward. While in some cases it may be possible to operate the wicket with but one cable and one series of idlers, we find that better 35 results are produced by the employment of another cable 20' and another series of idlers acting on the opposite side of the wicket in a manner similar to the first-named cable and series of idlers hereinbefore described. By 40 the employment of two cables and two series of idlers the wicket operates more smoothly and easily.

The cable 31', or the "lower cable," engages the lower slot or groove on the periphery of the drum and is preferably fastened to the drum at or near a point marked 45 "B." This cable then engages the lower slot or groove on the periphery of the drum for a certain distance and after leaving the drum passes over the idler 22' which is mounted on a bracket 30' secured in any manner to the post 3'. The cable then takes 50 a downward direction passing over the idler 24' which is secured to the post 3' and then an upward direction over the idler 23' which is also mounted on the bracket 30' and then to and over the idler 21', which is secured by 55 its hanger or bracket to the under side 10 of

the desk or counter 6. The cable 20' is then brought to and engages the lower slot or groove on the periphery of the drum and runs back to its starting point B. A cable-clamp 35' is preferably integrally united 60 with the tie-rod 7 and firmly clamps the cable 21' to the stilt 5'.

We have also provided counterweights 36 and 36' which are respectively fastened to the cables 20 and 20' in any manner and at 65 points preferably immediately below the idlers 22 and 22' as illustrated. The counterweight accomplish the same purpose as those ordinarily used in the case of windows and by their use the wicket remains in 70 any desired position and it is prevented from falling by its own weight by the action of the counterweights. Obviously the counterweights might be attached to the wicket independently of the operating mechanism if 75 it is so desired, but because of the simplicity of the manner of their use and the obviating of superfluous mechanism, we prefer to attach them to the cables in the manner we have described.

We have also provided guides 41, 42 and 43 which are arranged at intervals about the periphery of the drum as illustrated, and which are preferably attached in any desirable manner to the under side of the desk 80 or counter. These guides fit up closely to the drum and are provided with arms parallel to the upper and lower surfaces of the drum, their function being to prevent the cables from slipping out of their respective 85 grooves or slots on the periphery of the drum.

A spring catch 50 is provided near the left-hand end of the supporting-bar 14. When it is desired to close the wicket the operating handle 16 is pushed or thrust to the left from a position at the right of the supporting-bar 14 as has been explained. When the operating bar 11 comes into engagement with the spring-catch 50, the latter is forced downward and then rises automatically due to its spring action upon its disengagement with the operating-bar. Thus when the wicket is shut or closed, the operating-bar takes a position on the extreme left of the supporting-bar 14 and the wicket is then locked and cannot be raised by anyone on the outside of the counter or desk. The knuckle-joint 13 hereinbefore mentioned has been provided in order to permit the operating-bar 11 to be raised vertically if it should become "stiff" or "caught" or to permit the operating-bar to be raised over the spring-catch 50.

It will be understood that our operating 125 device is not limited in use to bank screen wickets but it may also be applied to windows or to any other analogous uses. It will be understood also that our invention is not limited to the exact details of con- 130

struction and the arrangement of parts herein shown and described, such being for the purpose of illustration only, but various modifications may be resorted to without departing from the spirit of our invention as set forth in the appended claims.

What we claim as our invention is:—

1. In a device of the character described, the combination with a support, a wicket 10 mounted at the front of said support, a drum pivoted in a horizontal plane and depending from the under side of the support, an endless cable encircling the periphery of said drum and attached thereto, a series of idlers mounted below said counter over which said endless cable passes, said endless cable being also attached to said wicket and means disposed at the rear of said support for rotating said drum to raise 20 or lower the wicket.

2. In a device for operating bank screen wickets, the combination with a support, a wicket mounted at the front of said support and slideable vertically, a horizontal drum 25 pivotally mounted on said support and in a plane transverse to the plane of the wicket, means operatively connecting said horizontally disposed drum with the vertical wicket and operating means secured to said drum 30 at the rear of the support whereby said wicket may be manually raised and lowered by a rotary movement of said drum.

3. In a device for operating bank screen wickets, the combination with the wicket, of 35 a support, a horizontal drum pivotally mounted on said support, an endless cable engaging the periphery of said drum and fastened thereto and to the wicket, a counterweight attached to said endless cable and adapted by its action to retain said wicket 40 in any given position, a series of idlers over which said cable passes, said cable being adapted to raise or lower the wicket by a rotary movement of said drum, a handle secured to said drum for manually rotating 45 the same, and means whereby said wicket is

automatically locked when in closed position.

4. In a device for operating bank screen wickets, the combination with the wicket, of 50 stilts or rods fastened to said wicket, a support, a drum pivotally mounted on said support and in a plane transverse to the plane of said wicket, and means for raising or lowering said wicket upon a rotary move- 55 ment of said drum and consisting of two endless cables each attached to said drum and to one of said stilts or rods and a series of idlers over which said cables pass.

5. In a device for operating bank screen 60 wickets, the combination with the wicket, of stilts or rods fastened to said wicket, a support, a tie-rod connecting said stilts for supporting the same, a drum pivotally mounted on said support and in a plane transverse 65 to the plane of said wicket, an operating-bar fastened to said drum, a supporting-bar on which said operating-bar rests, two endless cables engaging the periphery of said drum and fastened thereto, a series of 70 idlers for each of said cables over which said cables pass, means connected with said tie-rod for fastening said cables to said stilts, means on said supporting-bar for automatically locking said wicket when in 75 closed position, means for preventing said cables from slipping off the periphery of said drum, means for preventing said wicket, when opened, from falling by the force of gravity, said cables being adapted to give a 80 vertical motion to said wicket in order to raise or lower the same upon a lateral movement of said operating-bar.

Signed at Brooklyn in the county of Kings and State of New York this 5th day 85 of June A. D. 1914.
